(57) **CLAIM**

The ornamental design for a multiple compartment contraceptive compact case, as shown and described.

DESCRIPTION

FIG. 1 is a front-left top perspective view for a multiple compartment contraceptive compact case, showing my new design in a closed configuration;

FIG. 2 is a front elevational view of FIG. 1 thereof;

FIG. 3 is a rear elevational view of FIG. 1 thereof;

FIG. 4 is a left side elevational view of FIG. 1, the right side elevational view being a mirror image thereof;

FIG. 5 is a top plan view of FIG. 1 thereof;

FIG. 6 is a bottom plan view of FIG. 1 thereof;

FIG. 7 is a front-left perspective view for a multiple compartment contraceptive compact case of FIG. 1 in an open configuration thereof;

FIG. 8 is a front perspective view of FIG. 7 thereof;

FIG. 9 is a rear perspective view of FIG. 7 thereof;

FIG. 10 is a left side perspective view of FIG. 7, the right side perspective view being a mirror image thereof;

FIG. 11 is a top perspective view of FIG. 7 thereof; and,

FIG. 12 is a bottom plan view of FIG. 7 thereof.
